ROTARY AIR COMPRESSOR

Filed Dec. 14, 1927

FIG - 1

FIG - 2

INVENTOR.

Warren C. Tyler.

BY Bert Russell

ATTORNEY.

UNITED STATES PATENT OFFICE

WARREN C. TYLER, OF LOS ANGELES, CALIFORNIA

ROTARY AIR COMPRESSOR

Application filed December 14, 1927. Serial No. 239,927.

My present invention is referred to as a rotary air compressor for the reason that it is particularly designed for use in producing moderate excess pressures,—such as pressures exceeding atmospheric by only two or three pounds; but it should be understood that rotary units such as are herein described are also entirely suitable to be introduced into gas mains, or the like, to obviate the necessity for employing very high pressures at the inlet ends of such mains, in order satisfactorily to deliver gas to remote points,—under an acceptable pressure and/or at a desired rate.

It is an especial object of this invention inexpensively to provide relatively simple and rugged blower or compressor units utilizing two or three or a larger number of fans,—a central fan, of comparatively large diameter, being preferably employed between feeder fans which are so disposed relatively thereto as to produce an equalization of end thrusts. All moving parts of my units may be eccentrically positioned within a suitable housing and so supported that, when driven by an inexpensive exterior motor (not shown) a shaft which may be common to the compressor and the mentioned motor may practically "float" during its rapid rotation.

Other objects of my invention, including the optional use of special inlet connections and special bearings, and the incorporation of a stream-lined central disc in the largest of the mentioned fans (hereinafter referred to as a "booster fan") may be best appreciated from the following description of an illustrative embodiment of my invention, taken in connection with the appended claims and the accompanying drawings, in which

Fig. 1 is a horizontal sectional view, taken substantially as indicated by the broken line A—A of Fig. 2, but with parts broken away to various levels.

Fig. 2 is a side elevational view, taken substantially as indicated by the arrow B, but with parts broken away and a lateral feed fan omitted.

In that embodiment of my invention chosen for purposes of illustration, I show a pair of oppositely-acting lateral fans, respectively comprising blades 1, 1', as adapted, when

rotated in the direction indicated by arrows, to force air or any gas inward toward flattened and slightly concaved conical surfaces 2, 2'' of a bilaterally symmetrical booster fan 3. The fan 3 comprises suitably spaced reaction elements or "spanker" blades 3', 3'', shown as projecting from the surfaces 2, 2'; and all of the mentioned fans may be confined within a suitable housing,—such as a two-part housing comprising a main element 4 and a removable side element 5, these parts being concave and associated with subsidiary housing elements in the form of intakes 6, 6'. The last-mentioned elements are adapted not only to receive a shaft 7, provided with suitable bearings (ball bearings being suggested at 8 and 8') but to admit air or other gas thru spaced openings 9, 9'.

The side element 5 of the described housing being rigidly but removably secured in any suitable manner (as, by screws 10) and the booster fan 3 being eccentrically disposed therein, any gas entering the openings 9, 9' (as, from a feed main 11) is so powerfully fed by the radial fans 2, 2' and radially advanced by the booster fan 3 as to be delivered to any outlet 12 at a considerably increased velocity—implying a corresponding pressure differential.

When my described compressor unit is used to deliver ordinary air, the special intake connections 6, 6' may be dispensed with; but when such a unit is used at an intermediate point in a gas main, to secure a satisfactory rate of flow and/or delivery pressure, the feed main 11 may be connected with the intake openings 9, 9' by means comprising, in addition to the mentioned optional connections 6, 6', a so-called Y—13. Separable joints are suggested as suitable for the removable attachment of the mentioned Y with the intake connections 6, 6' (one of these being apertured for the motor shaft 7 when the mentioned motor is external); said connections may be secured in place by threaded or other joints; the outer elements of any bearings 8, 8', when separately formed, may be secured by a mere "press fit" or otherwise,—the order of assembly being obvious; and means such as suitable shoulders upon the 100

shaft 7 may be relied on laterally to center a central disc or web 14, comprised in the booster fan 3, with reference to the main housing described,—the lateral clearance there-
5 between being preferably very limited.

It will be seen that the fans 1, 1', as rotated by the shaft 7 or its equivalent, so force air or gas toward the disc 14 (preferably provided with the mentioned concavo-conical
10 surfaces 2, 2', favorable to a radial component in the flow thereover) as to produce a substantial balance of thrusts upon the shaft 7. The latter is presumed to be identical with or directly coupled to the shaft of a
15 suitable electric or other motor, immaterial to this invention, and the booster fan 3, of larger diameter and correspondingly higher peripheral speed, is thus constantly fed, by fans, 1, 1', with air or gas to be "spanked"
20 outward by the stream-lined blades 3, 3',—for delivery into a substantially crescent-shaped chamber or space 15 and thence thru any suitable outlet 12, the illustrated outlet being integral with the main housing element
25 5. The provision of the disc 14 in fact, permits material pressure to be built up adjacent the axis of the booster fan 3, so that the flow of gas transversely of the path of delivery of fan 3 will help this fan to deliver
30 gas not only at a higher velocity, but at considerably increased pressure. The transverse feeder fans 1, 1' are purposely made large enough to secure this excess pressure.

It will be obvious that when my compressors are used in the delivery of illuminating gas, or the like, rather than ordinary air, usual or special packings and glands may be employed as required; and that both the eccentric position, with a minimum clearance
35 at 16, and the mentioned small lateral clearances of the blades 3, 3' of the booster fan 3 (as compared with the clearances of the feeder fans 1, 1') as well as the provision of sharp "leading" and "following" edges on
40 blades 3, 3' are favorable to high efficiency; and also that, whether or not the hubs or other parts of the described fans are united with one another but separate from shaft 7, all parts may be inexpensively formed by
45 such operations as casting and die-pressing; but I may state that my novel, simple and efficient compressor units (in which I may employ any even or uneven number of fans related in the described manner) are more
50 particularly intended for the inexpensive production of moderate pressures or vacua,—such as two or three pounds above or below atmospheric pressure.

Although I have herein described a single
60 complete embodiment of my invention, it will be obvious that an application of the principles of this invention to the handling of liquids, rather than gases, or even to the generation of power by the interposition of a
65 suitable unit in a stream of fluid, would re-

quire only an intelligent re-design of my unit for the particular purpose in view; and I accordingly emphasize, in conclusion, the fact that various parts of this unit might be independently used, and also the fact that 70 numerous modifications thereof might easily be devised,—without involving even a slight departure from the spirit and scope of this invention, as indicated above and in the following claims.

Claims:

1. For use in a unit of the general character described: a two-part housing whose respective parts are provided with lateral gas-admission openings; bearings in said 80 housings; a pipe; subsidiary housing elements adapted to cover said bearings and connecting between said lateral openings and said pipe; lateral delivery fans, one at each side of the housing and drawing in gas at 85 the openings; and a booster fan centrally disposed between the lateral delivery fans.

2. For use in a unit of the general character described: a two-part housing whose respective parts are provided with lateral gas 90 admission openings; bearings in said housings; a pipe; subsidiary housing elements adapted to cover said bearings and connecting between said lateral openings and said pipe,—said pipe comprising a Y to which said 95 subsidiary housing elements are removably secured; lateral delivery fans, one at each side of the housing and drawing in gas at the openings; and a booster fan centrally disposed between the lateral delivery fans.

In witness whereof, I have hereunto affixed my signature.

WARREN C. TYLER.
